2,308,999

COKE OVEN DOOR

Earl E. Moore, Gary, Ind.

Application August 3, 1940, Serial No. 350,501

10 Claims. (Cl. 202—248)

This invention relates to coke oven doors and particularly to an improved coke oven door of the pusher side self-sealing type.

It is the common practice to provide a battery of by-product coke ovens, that is, a plurality of coke ovens in side by side relation for processing coke. Each of these ovens usually consists of a relatively high and narrow longitudinally extending chamber having substantially a rectangular cross-section and an opening in the rear end thereof for discharging the coke therefrom and an opening at the opposite or front end through which a pusher ram enters thereinto for forcing and delivering the coke from the chamber through the discharge opening from the oven.

The gases distilled off during the coking process, as is well known, constitute a very valuable by-product and for this reason, it is important that the openings in the opposed ends of the coke oven chamber be tightly sealed.

Various types of doors and closures have been suggested and used for closing these openings. While several of these doors have been successful in their use, they were usually complicated and expensive in their construction. Also, the doors heretofore used were necessarily heavy and cumbersome and usually necessitated the use of mechanism, such as door extractors, to remove the doors from and replace them over the openings of the oven. In the practice in the past, it was necessary first to remove the door from the opening and to hold it while the coke was pushed from the oven. Thus, it will be seen that this practice not only consumed an excessive amount of time, but mechanism, such as a door extractor in addition to the pusher ram was necessary to remove and hold the door while the pusher ram removed the coke from the oven. Furthermore, tarry vapors distilled off the coal during the coking process condensed to a certain extent and deposited along the inner edges of the door and the frame, which eventually affected the seal therebetween and necessitated frequent cleaning of the tar deposit from the door and the frame which had partly become carburized and thus became difficult to remove.

Also, most doors heretofore suggested and used employed a complicated locking mechanism for locking the same in place which was oftentimes not only difficult to manipulate but also expensive in its construction and usually required additional tools for actuating the same.

In the present invention, there is provided an improved self-sealing coke oven door which is disposed within the oven chamber at all times

and made a part of the pusher ram when it is in operation eliminating the need for any additional door removing mechanism, such as a door extractor, and at the same time, a door construction which eliminates any tar deposit remaining thereon and consequent carburization, as such deposit is automatically burned off the door as it passes through the oven chamber after each charge has been processed.

Accordingly, it is one of the objects of the present invention to provide an improved coke oven door which is simple and inexpensive in its construction and, at the same time, one which is effective and more efficient than any coke oven door heretofore proposed.

It is another object of the invention to provide an improved coke oven door which is disposed with the coke oven chamber and made a part of the pusher ram during the removal of the coke from the oven.

It is a further object of the invention to provide an improved coke oven door which is self-sealing and effectively seals the opening against leakage at all times.

It is still another object of the invention to provide an improved coke oven door having a simple and inexpensive locking means incorporated therewith thereby eliminating such complicated locking mechanism as heretofore used on such doors.

Various other objects and advantages of this invention will be more apparent in the course of the following specification and will be particularly pointed out in the appended claims.

In the accompanying drawings there is shown, for the purpose of illustration, one embodiment which my invention may assume in practice.

In these drawings:

40 Figure 1 is a longitudinal section through a coke oven showing the improved door of my invention incorporated therewith;

45 Figure 2 is an enlarged horizontal section through a portion of the front opening in the oven showing my improved door in locked position;

50 Figure 3 is a section taken on line III—III of Figure 2 showing the door in its locked position;

Figure 4 is a section similar to Figure 3 showing the door in its unlocked position;

55 Figure 5 is a front elevation of the coke oven showing my improved door in locked position;

Figure 6 is a section taken on line VI—VI of Figure 5; and,

Figure 7 is a section taken on line VII—VII of Figure 5.

Referring more particularly to the drawings, there is shown in Figure 1 a coke oven consisting of a substantially rectangular-shaped longitudinally extending chamber 2 having a discharge opening 3 arranged at the rear end thereof for discharging the coke therefrom and an opening 4 arranged at the opposite end thereof in the front side of the oven through which the pusher ram (shown in broken lines) is adapted to move to force the coke from the oven with which the improved door of my invention is shown incorporated for the purpose of illustration.

According to the present invention, there is arranged within the oven chamber for closing the opening 4 in the front side thereof, a door 5 which consists of a rigid rectangular-shaped metallic plate-like member or casting 6 which is slightly smaller than the rectangular cross-section of the oven chamber. There is arranged on the inner side of the plate member 6 substantially centrally thereof, in any suitable manner, preferably a vertically extending reinforcing I-beam member 7 or any other suitable type of stiffening member around which a suitable refractory lining 8 is disposed. There is arranged on the outer side of the plate member 6 in a suitable manner, preferably by means of welding, a metallic plate-like diaphragm 9, preferably made of relatively thin steel which is preferably spaced from the outer surface of the plate-like member 6 by horizontally extending spaced apart raised portions 10 integrally arranged with the plate member 6 on the outer side thereof. There is arranged on the outer surface of the diaphragm 9 around the edges thereof and attached thereto in any suitable manner, preferably by means of welding, a sealing member 12 which is T-shaped in the present instance, but it will be understood that this sealing member may be made of angle-iron or any other suitable structural shape. The outer or sealing edge of the sealing member 12 has preferably a knife-like edge portion 13 for a purpose hereinafter to be described. To offset any warping of the casting 6, the diaphragm 9 may be adjusted in relation to the casting 6 by means of a plurality of set screws or wedges (not shown), so that the diaphragm 9 may be maintained straight in relation to the oven frame 17, at all times, thereby providing a uniform, tight fitting bearing of the sealing member 12 against the oven frame 17. There is also carried by the diaphragm 9 preferably just inside of the vertical sealing member 12 along the opposite vertical sides of the door, a plurality of spaced apart hook-like lugs 14 which extend outwardly from the outer surface to which they are suitably attached preferably by means of welding. The inner surfaces of each of the end portions of each of the lugs are substantially wedge-shaped and are tapered downwardly and outwardly as at 15 for a purpose later to be described. There is also attached to the outer surface of the diaphragm 9 substantially centrally thereof, preferably a pair of attaching members or lugs 16 to which the pusher ram is adapted to be removably attached for manipulating the door and to remove the coke from the oven chamber.

There is arranged around the opening 4 in the front side of the oven, a metallic frame 17 which 75

consists preferably of a structural member having substantially a U-shaped cross-section arranged around the opening in the front wall of the furnace which is held in place against the oven brickwork preferably by buckstays 18 which bear against an outwardly extending flange 19 carried by the U-shaped frame members. There is also carried by the U-shaped frame members an inwardly extending flange portion 20 having preferably a plurality of openings 21 arranged along the vertical inner edges thereof and spaced apart a distance substantially equal to the distance apart of the hook-like lugs 14 carried by the diaphragm 9 of the door with which they are adapted to cooperate. There is arranged on the outer surface of the flanges 20 immediately below each of the openings 14 therein, a boss portion 22 having an outer tapered surface 23 preferably corresponding to the inner tapered surface 15 of the hook-like lugs 14 with which they are adapted to cooperate.

The improved door of my invention operates in the following manner:

It will be understood that the complete door 5 is adapted to be part of the pusher ram when the pusher ram forces the coke from the oven. That is, the door is the end portion of the pusher ram and bears directly against the coke in discharging the same from the oven chamber. The end of the pusher ram is attached to the attaching lugs 16 arranged on the front side of the door as shown in Figure 4 of the drawings, and the pusher ram mechanism moves the door upwardly so that the inner tapered portions 15 of the hook-like lugs 14 are lifted out of contact with the outer tapered portions 23 of the boss portions 22 carried by the frame. That is, the door is moved to its extreme upper position as shown in Figure 4 of the drawings. The pusher ram is then moved longitudinally of the oven chamber and passes through the opening 4 in the front side of the oven and through the oven chamber carrying with it the door 5 which forces the coke from the oven through the discharge opening 3 in the opposite end thereof and moves to a position substantially as shown in the broken lines of Figure 1 of the drawings.

After the coke has been removed from the oven, the movement of the pusher ram together with the door carried on the end thereof, is reversed and moves back through the oven chamber to its initial position as shown in Figure 4. As the door 5 reaches the front side of the oven, the hook-like lugs carried by the diaphragm of the door pass through the openings 21 arranged in the opposed edges of the flanges 20 of the frame. When the door reaches this position, it is then moved downwardly by the pusher ram mechanism and the inner tapered portions 15 of the lugs 14 contact the outer tapered portions 23 of the boss portions 22 thereby forcing the knife-like edge portions 13 of the sealing members 12 against the inner surface of the flange 20 carried by the frame so as to completely seal the opening against leakage and at the same time securely locking the door in place over the opening, as shown in Figure 3 of the drawings. That is to say, the end portions of the hook-like lugs cooperate with the boss portions below the openings arranged in the frame and tend, through a camming action, to securely lock the door in place over the opening and it is securely held in locked position due primarily to its own weight as shown in Figures 3 and 5 of the drawings.

It will be seen that such a construction per-

mits the use of a smaller or shorter door than any door disposed on the outside of the frame. In using the door of the construction of the present invention, the oven chamber is not completely filled, but an empty space must necessarily be provided above the layer of coal in the chamber so as to permit the free escape of gases which are being distilled off the coal during the processing and also to permit leveling of the coal to a uniform depth throughout the chamber as is well known to those skilled in the art. In the present construction, it is preferable that there is arranged with the frame 17 and in the front side of the oven wall above the door 5, an opening 24 which is closed preferably by a suitable door 25 carried by the frame. It will be understood that the leveling bar is inserted through the opening 24 into the upper part of the oven chamber to level the coal therein to a uniform depth as desired.

As a result of my invention, it will be seen that there is provided a door of a simple and inexpensive construction which effectively seals the front side of the opening on the oven chamber against the leakage, thereby preventing the escape of the valuable by-product gases therefrom. It will also be seen that my improved door is self-sealing, and self-locking, thereby eliminating the need for any auxiliary sealing means and any expensive locking mechanism. It will also be seen that the door of the present invention becomes a part of the pusher ram when the coke is being removed from the oven and acts to push the coke therefrom thereby dispensing with any additional means for holding or supporting the door while the coke is being removed from the oven chamber. It will be seen further that the knife-like edges 13 of the sealing members 12 permit substantially a point contact and tend to cut and eliminate any deposit accumulated on the inner sides of the flange 20 of the frame to provide a perfect seal. Furthermore, if the door frame is uneven, the diaphragm, due to its flexibility, will yield and the sealing members will not become distorted or damaged.

While I have shown and described in this application an embodiment of my invention, it will be understood that this embodiment is merely for the purpose of illustration and description and that various other forms may be devised within the scope of the invention, as defined in the appended claims.

I claim:

1. In combination with a coke oven having a discharge opening arranged at one end thereof for discharging the coke therefrom and an opening arranged at the opposite end thereof in the front side of the oven, a door arranged within the oven chamber for closing said opening in the front side thereof, a frame arranged around said front opening, a flange carried by said frame extending transversely of said opening whereby the removal of the door from the oven is opposed, means carried by said door which is adapted to cooperate with said flange to securely seal said front opening against leakage, and means for locking said door securely in engagement with said frame, said door adapted to be moved through the oven chamber so as to force the coke therefrom through the discharge opening in the opposite end thereof.

2. In combination with a coke oven having a discharge opening arranged at one end thereof for discharging the coke therefrom and an opening arranged at the opposite end thereof in the

front side of the oven, a door arranged within the oven chamber for closing said opening in the front side thereof, a frame arranged around said front opening, a diaphragm arranged on the outer side of said door, means carried by said diaphragm which is adapted to cooperate with said frame to securely seal said front opening against leakage, and means for locking said door securely in engagement with said frame, said door adapted to be moved through the oven chamber so as to force the coke therefrom through the discharge opening in the opposite end thereof.

3. In combination with a coke oven having a discharge opening arranged at one end thereof for discharging the coke therefrom and an opening arranged at the opposite end thereof in the front side of the oven, a door arranged within the oven chamber for closing said opening in the front side thereof, a frame arranged around the outer side of said front opening, a plate-like diaphragm arranged on the outer side of said door, means carried by said diaphragm which is adapted to cooperate with said frame to securely seal said front opening against leakage, and a plurality of spaced apart hook-like lugs arranged along the opposed sides of said door which are adapted to cooperate with means arranged on said frame for locking said door securely in engagement with said frame, said door adapted to be moved through the oven chamber so as to force the coke therefrom through the discharge opening in the opposite end thereof.

4. In combination with a coke oven having a discharge opening arranged at one end thereof for discharging the coke therefrom and an opening arranged at the opposite end thereof in the front side of the oven, a door arranged within the oven chamber for closing said opening in the front side thereof, a frame arranged around the outer side of said front opening, a plate-like diaphragm arranged on the outer side of said door, means carried by said diaphragm which is adapted to cooperate with said frame to securely seal said front opening against leakage, a plurality of hook-like lugs arranged along the opposed sides of said door with the inner surface of the end portion of each of them tapered outwardly, and a corresponding number of boss portions arranged on the outer side of said frame opposite said hook-like lugs with each having an outer tapered surface corresponding to the inner tapered surface of the end portion of said lugs, the end portion of the hook-like lugs adapted to cooperate with the boss portions arranged on said frame to lock the door securely in engagement with said frame, said door adapted to be moved through the oven chamber so as to force the coke therefrom through the discharge opening in the opposite end thereof.

5. In combination with a coke oven having a discharge opening arranged at one end thereof for discharging the coke therefrom and an opening arranged at the opposite end thereof in the front side of the oven, a door arranged within the oven chamber for closing said opening in the front side thereof, said door consisting of a rigid inner metallic member having a refractory lining arranged on the inner side thereof, a plate-like diaphragm arranged on the outer side of said rigid inner metallic member, a frame arranged around the outer side of said front opening, means arranged around the edges of said diaphragm which is adapted to cooperate with said frame to securely seal said front opening against leakage, and means carried by said door which is adapted to cooperate with means car-

ried by said frame for locking said door securely in engagement therewith, said door adapted to be moved through the oven chamber so as to force the coke therefrom through the discharge opening in the opposite end thereof.

6. The combination as defined in claim 5 wherein the means for locking said door securely in engagement with said frame consists of a plurality of spaced apart hook-like members arranged along the edges of said door which are adapted to extend through openings arranged in said frame and cooperate with a corresponding number of boss portions arranged on the outer side of said frame.

7. In combination with a coke oven having a discharge opening arranged at one end thereof for discharging the coke therefrom and an opening arranged in the opposite end thereof in the front side of the oven, a door arranged within the oven chamber for closing said opening in the front side thereof, said door consisting of a rigid inner metallic member having a refractory lining arranged on the inner side thereof, a plate-like diaphragm arranged on the outer side of said rigid inner metallic member, a frame arranged around the outer side of said front opening having an inwardly extending flange integrally arranged therewith therearound, means arranged around the edge of said plate-like diaphragm having a knife-like edge which is adapted to cooperate with the inwardly extending flange of said frame to securely seal said front opening against leakage, and means carried by said door which is adapted to cooperate with means carried by said flange for locking said door securely in engagement therewith, said door adapted to be moved through the oven chamber so as to force the coke therefrom through the discharge opening in the opposite end thereof.

8. In combination with a coke oven having a discharge opening arranged at one end thereof for discharging the coke therefrom and an opening arranged in the opposite end thereof in the front side of the oven, a door arranged within the oven chamber for closing said opening in the front side thereof, said door consisting of a rigid inner metallic member having a refractory lining arranged on the inner side thereof, a plate-like diaphragm arranged on the outer side of said rigid inner metallic member, a frame arranged around the outer side of said front opening having an inwardly extending flange integrally arranged therewith therearound, means arranged around the edge of said plate-like diaphragm having a knife-like edge which is adapted to cooperate with the inwardly extending flange of said frame to securely seal said front opening against leakage, a plurality of spaced apart hook-like lugs carried by said diaphragm and

extending outwardly therefrom, said hook-like lugs adapted to extend beyond the flange carried by said frame and to cooperate with a corresponding number of boss portions arranged on the outer side of said flange for locking said door securely in engagement therewith, said door adapted to be moved through the oven chamber so as to force the coke therefrom through a discharge opening in the opposite end thereof.

9. In combination with a coke oven having a discharge opening arranged at one end thereof for discharging the coke therefrom and an opening arranged at the opposite end thereof in the front side of the oven, a door arranged within the oven chamber for closing said opening in the front side thereof, a frame arranged around said front opening, a flange carried by said frame extending transversely of said opening whereby the removal of the door from the oven is opposed, means carried by said door which is adapted to cooperate with said flange to securely seal said front opening against leakage, means for locking said door securely in engagement with said frame, said door adapted to be moved through the oven chamber so as to force the coke therefrom through the discharge opening in the opposite end thereof, and means carried by the front side of said door for holding and supporting the same while it is being moved through the oven chamber.

10. In combination with a coke oven having a discharge opening arranged at one end thereof for discharging the coke therefrom and an opening arranged at the opposite end thereof in the front side of the oven, a door arranged within the oven chamber for closing said opening in the front side thereof, means carried by said door which is adapted to cooperate with means carried by said oven around the opening in the front side thereof for sealing the same against leakage, cooperable means arranged on the outer side of said door and the inner side of said front opening for locking the door in position thereover consisting of a plurality of hook-like lugs arranged along the opposed sides of said door with the inner surface of the end portion of each of them tapered outwardly, and a corresponding number of boss portions arranged on the outer side of said opening opposite said hook-like lugs with each having an outer tapered surface corresponding to the inner tapered surface of the end portion of said lugs, the end portion of the hook-like lugs adapted to cooperate with the boss portions arranged on said frame to lock the door securely in position over said opening, said door adapted to be moved through the oven chamber so as to force the coke therefrom through the discharge opening in the opposite end thereof.

EARL E. MOORE.
